James R. Binns.

UNITED STATES PATENT OFFICE.

JAMES R. BINNS, OF CANTON, OHIO, ASSIGNOR OF ONE-HALF TO EDWIN D. MYERS, OF CANTON, OHIO.

EXPLOSIVE-ENGINE STARTER.

1,148,071.

Specification of Letters Patent.

Patented July 27, 1915.

Application filed October 31, 1914. Serial No. 869,593.

To all whom it may concern:

Be it known that I, JAMES R. BINNS, a citizen of the United States, residing at Canton, in the county of Stark and State of Ohio, have invented a new and useful Explosive-Engine Starter, of which the following is a specification.

My invention relates to explosive engine starters and has more especial reference to 10 a device, adapted to replace the ordinary crank used for starting automobile engines. This device is adapted for more conveniently turning over the engine shaft, the mechanism being so arranged that the operator may have greater advantage in properly applying the necessary power for starting the engine.

The objects of my invention are, to generally improve engine starters and to provide such a device as may enable the operator to start the engine without inconvenience or danger, to permit the operator to start the engine with a minimum exertion, the device being easily and conveniently operated and 25 capable of being applied to or removed from the engine practically as a unit without the necessity of altering the construction of said engine.

Another object is to provide a device 30 which will be out of engagement with the engine shaft and idle during the time the engine is running and which is only thrown into engagement with the engine shaft when it is desired to start the engine.

With these objects in view the invention 35 consists in the novel construction and arrangement of parts, hereinafter described, illustrated in the accompanying drawings, and particularly pointed out in the appended 40 claims, it being understood that various changes in the form, proportions, size and minor details of construction may be made within the scope of the appended claims without departing from the spirit or sacrificing any of the advantages of the invention.

Referring to the accompanying drawings: Figure 1 shows a top plan view of a portion of an automobile chassis and engine showing my explosive engine starter applied thereto. Fig. 2 is an enlarged longitudinal sectional view taken through my explosive engine starter. Fig. 3 is a section on line 3—3, Fig. 1. Fig. 4 is a top plan 55 view of a portion of my device, parts being

broken away for the purpose of illustration. Fig. 5 is a section taken on line 5—5, Fig. 4. Fig. 6 is a side elevation of a portion of my device, parts being broken away for the purpose of illustration. Fig. 7 is a vertical 60 sectional view through the compound pulley used in my device. Fig. 8 is a fragmentary elevation of a portion of the operating pedal, showing the outer side of said pedal.

Similar numerals of reference indicate 65 corresponding parts throughout the several figures of the drawings.

Referring more especially to the construction illustrated in the accompanying drawings, the numeral 1 indicates a portion of the chassis of an automobile and the numeral 2 the engine, which may be of any usual type of internal combustion engines.

The numeral 3 indicates the engine shaft to which shaft is secured by means of the pin 4 the usual cylindrical member 5, which is provided with the clutch member 6 such as is ordinarily provided upon the engine shaft for the purpose of cranking the engine. Secured to the cylindrical member 5 by means of screws 7 or their equivalents is a clutch member 8 provided with a series of teeth 9. The usual crank 10 such as is ordinarily used for cranking an automobile engine is suitably journaled in a bearing 11 mounted upon the chassis 1. The usual clutch member 12 is connected to the inner extremity of the crank 10 by means of a screw 13.

Loosely mounted upon the member 12 is 90 a sliding sleeve 14 which is provided with a spoke 15, which spoke supports a segment 16 provided with a peripheral groove 17, said segment adapted to rotate around the outside of the housing 18 as best shown in Fig. 5 of the drawing. To the inner extremity of the sleeve 14 is connected a clutch member 19 by means of screws 20 or their equivalent, said clutch member being adapted to engage the clutch member 8 as hereinafter described.

A coil spring 21 is located 95 around the sleeve 14, one end of said spring being bent around the spoke 15 shown at 22, the other end of the spring resting in a notch 23 in the housing 18, the spring thus 100 normally tending to hold the segment 16 in the position best illustrated in Figs. 5, 6 and 7. This spring also tends to normally throw the clutch member 19 into engagement with the member 8.

A pair of arms 24 and 24^a, provided with inclined forward faces 25 are bolted to the base of the engine 2, the forward inclined faces being adapted to be engaged by the spoke 15 of the segment as will be herein-after described and pointed out. Connected at one end of the segment 16 by means of a screw 26 is a chain 27 which is located around the groove in the segment and then passes over the compound pulley 28. The compound pulley is composed of a large sheave 29, and a small sheave 30, which are preferably made integral, the chain 27 passing first around the large sheave and then 10 up and around the smaller sheave as best shown in Figs. 1 and 3 of the drawings. The chain is then continued back along the frame of the machine over a guiding pulley 31 and around the segment 32 being attached to the rear extremity of said segment. The segment 32 is pivoted at 33 upon a suitable axle which is connected to the side wall 34 of the automobile as shown. A foot lever 35 is provided with a sleeve 36 which has 15 a bearing upon the axle 33, said foot lever being provided with a downwardly depending arm 37 which is adapted to be contacted with a set screw 38 located through a lug 39 in the segment 32. A bracket 40 extends 20 downwardly from the axle 33 and is supported upon the channel frame of the chassis 1. The foot lever 35 is normally held in the position shown in Fig. 3 by means of a spring 41 mounted upon the dash board 42 25 of the automobile, the shoulder 43 of the spring engaging the lug 44 upon the end of the foot pedal.

The operation of the device is as follows: The parts are normally held in the position 40 shown in Figs. 1 and 3; the foot pedal 35 being held forward by means of the spring 41. The segment 16 is thus held in the position shown in Fig. 1 and in dotted lines 45 in Fig. 5, as the chain is thus drawn back by means of the segment 32. In this position the spoke 15 will be engaged by the inclined face 25 of the arm 24, thus holding the clutch member 8 out of engagement with the clutch member 19. When it is desired 50 to start the engine the spring 41 is pushed back with the foot releasing the lever 35 and allowing it to assume a vertical position. The pull being thus removed from the chain 27 allowing the spring 21 to throw 55 the segment 16 into the position shown in Figs. 5, 6 and 7, the spoke 15 engaging with the inclined face of the arm 24^a; holding the clutch members 8 and 19 out of engagement with each other. The foot pedal 35 is then 60 thrown forward again into the position shown in Figs. 1 and 3, the segment 16 being revolved, bringing the spoke 15 out of engagement with the inclined face of the arm 24^a and allowing the clutch member 8 65 to engage the clutch member 19 thus rotat-

ing the engine shaft 3. As the segment 16 completes its movement the spoke 15 will engage the inclined face upon the arm 24, thus throwing the clutch members again out of engagement as the engine is started. It will thus be seen that at all times while the device is not in operation, either while the engine is running or dead the clutch member 8 will be held out of engagement from the clutch member 19 and said clutch members are only thrown into engagement during the operation of starting the engine.

It will be noted that the entire device with the exception of the clutch member 8 is carried upon the spindle 45 of the crank 10. 80 This crank of course, is not necessary except when the driver of the car wants to start the engine from the outside when he can use the crank in the usual manner. The clutch member 12 upon the crank is normally held out of engagement with the clutch member 9 by the usual spring 46.

Although the drawings and above specification disclose the best mode in which I have contemplated embodying my invention I desire to be not limited to the details of such disclosure, for, in the further practical application of my invention, many changes in form and construction may be made, as circumstances require or experience suggests, 95 without departing from the spirit of the invention, within the scope of the appended claims.

I claim:

1. In an explosive engine starter, comprising in combination with an explosive engine, a receiving clutch member fixedly mounted upon the shaft of said engine, a movable clutch member slidably mounted upon the crank of said engine, a radial spoke provided upon said movable clutch member, a segment carried by said spoke, arms supported upon the engine base and located adjacent each side of said movable clutch member, inclined faces provided upon said arms, said spoke adapted to engage said inclined faces, means for normally holding said spoke in engagement with one of said inclined faces and means for rotating said segment.

2. In an explosive engine starter, comprising in combination with an explosive engine, a receiving clutch member fixedly mounted upon the shaft of said engine, a movable clutch member slidably mounted upon the crank of said engine, a radial spoke provided upon said movable clutch member, a segment carried by said spoke, arms supported upon the engine base and located adjacent each side of said movable clutch member, inclined faces provided upon said arms, said spoke adapted to engage said inclined faces, means for normally holding said spoke in engagement with one of said inclined faces, a flexible

member connected to said segment and a foot lever connected to said flexible member.

3. In an explosive engine starter, comprising in combination with an explosive engine, a receiving clutch member fixedly mounted upon the shaft of said engine, a movable clutch member slidably mounted upon the crank of said engine, a radial spoke provided upon said movable clutch member, a segment carried by said spoke, arms supported upon the engine base and located adjacent each side of said movable clutch member, inclined faces provided upon said arms, said spoke adapted to engage said inclined faces, means for normally holding said spoke in engagement with one of said inclined faces, a compound pulley, a chain connected to said segment and passing around said compound pulley and a foot lever connected to said chain.

4. In an explosive engine starter, comprising in combination with an explosive engine, a receiving clutch member fixedly mounted upon the shaft of said engine, a second shaft in alinement with said engine shaft, a movable clutch member slidably mounted upon said second shaft, a radial spoke provided upon said movable clutch member, a segment carried by said spoke, a half round casing located beneath said clutch members, cam members supported upon said casing and provided with inclined faces, a coil spring located around said movable clutch member and adapted to hold said spoke in engagement with one of said inclined faces, and means for rotating said segment.

5. In an explosive engine starter, comprising in combination with an explosive engine, a receiving clutch member fixedly mounted upon the shaft of said engine, a

second shaft in alinement with said engine shaft, a movable clutch member slidably mounted upon said second shaft, a radial spoke provided upon said movable clutch member, a segment carried by said spoke, a half round casing located beneath said clutch members, cam members supported upon said casing and provided with inclined faces, a coil spring located around said movable clutch member and adapted to hold said spoke in engagement with one of said inclined faces, a chain connected to said segment and a foot lever connected to said chain.

6. In an explosive engine starter, comprising in combination with an explosive engine, a receiving clutch member fixedly mounted upon the shaft of said engine, a second shaft in alinement with said engine shaft, a movable clutch member slidably mounted upon said second shaft, a radial spoke provided upon said movable clutch member, a segment carried by said spoke, a half round casing located beneath said clutch members, cam members supported upon said casing and provided with inclined faces, a coil spring located around said movable clutch member and adapted to hold said spoke in engagement with one of said inclined faces, a chain connected to said segment, a compound pulley, said chain passing around said pulley and a foot lever connected to said chain.

In testimony that I claim the above, I have hereunto subscribed my name in the presence of two witnesses.

JAMES R. BINNS.
